H. ROSEN

BUTTON

Filed July 24, 1922

Fig. 1,

INVENTOR
Hyman Rosen,
BY
Morris Hirschstein
ATTORNEY

UNITED STATES PATENT OFFICE.

HYMAN ROSEN, OF NEW YORK, N. Y.

BUTTON.

Application filed July 24, 1922. Serial No. 577,209.

To all whom it may concern:

Be it known that HYMAN ROSEN, citizen of the United States, residing at the city of New York, in the county and State of New York, has invented certain new and useful Improvements in Buttons, of which the following is a specification.

This invention relates to buttons. One object thereof is to provide a button of the character described having means whereby similarly constructed buttons may be readily secured or connected thereto in various arrangements and geometrical formation so as to provide ornamental devices adapted for use in decorating or draping garments, such as ladies' dresses and the like.

Another object is to provide a new and useful decorative or ornamental device for decorating or draping garments, such as ladies' dresses and the like, which shall be simple and cheap of manufacture and readily attachable to the garments.

Other objects of this invention will in part be obvious and in part hereinafter pointed out.

With these objects in view, the invention accordingly consists in the combinations of elements and arrangement of parts more fully set forth in the following description and of which the scope of application will be pointed out in the appended claims.

In the drawing accompanying this specification and forming part thereof and showing one illustrative embodiment of this invention,

Figure 1 is a vertical cross-sectional view of a button embodying my invention.

Fig. 2 is a cross-sectional view thereof cut along line 2—2 of Fig. 1; and

Fig. 3 is a plan view of an ornament adapted for decorating a garment, formed from a plurality of buttons embodying my invention and suitably arranged and interconnected.

Referring in detail to the drawing, particularly to Figs. 1 and 2, the button embodying this invention and there shown is seen to comprise two halves, 10, 11, the upper half 10 being of larger diameter than the lower half 11, which telescopes thereinto as will be clear from Fig. 1. The upper half forms the exposed face of the button and is accordingly suitably shaped to give an ornamental contour. Thus, in the form shown in the drawing, the upper half is substantially spheroidal in shape as shown

at 12. The upper half comprises a shaped shell 13, preferably of thin sheet metal and a covering 14 of cloth or the like suitable material. The lower half comprises a shell 15 and a like covering 16. The upper and lower halves are formed in suitable button dies, preferably such as described in my co-pending application, Serial Number 525,999 filed on the 30th day of December 1921, where I have fully described and claimed a button-making machine particularly adapted for making buttons embodying the present invention.

Extending from the periphery of the button are one or more stems 17. In the form shown in the drawing, this stem comprises a metal wire, but I contemplate also the use of braid, cord, or ribbon and like material for this purpose. The stem 17 is preferably inserted between the annular interfolded portions 14^a, 15^a, respectively, of the upper and lower halves of the button, the stem having an attaching portion 17^a bent substantially at right angles thereto, where wire is employed, and which attaching portion is secured between the telescoping halves of the button simultaneously with the closing of the two shells in the button-making process as more fully explained and described in my copending application for patent afore-mentioned.

In Fig. 3 is illustrated an ornament made of a cluster of buttons constructed in accordance with the present invention and consisting of a nucleus or central button 18, surrounded by circular rows of buttons 19 and 20 arranged concentrically about the nucleus 18. It will be seen that the row of buttons 19 comprises individual buttons interconnected by stems 19^a which are common to two contiguous buttons. Likewise the row of buttons 20 are interconnected by stems 28 common to two contiguous buttons of that row, and the inner row 19 is connected at intervals to the central button 18 by stems 19^b common to the central button and to the particular button of the row connected thereto. Likewise the row of buttons 20 is connected at intervals to the row 19 by stems 20^b common to two contiguous buttons of the two rows.

It will be noted that the buttons are so interconnected and arranged as to have their upper halves on the same side of the plane of the bottom of the button, so that the exposed faces cooperate to form a harmonious

group to give a neat and ornamental effect.

It will also be noted that the interconnecting of the individual buttons to each other and of the rows to each other and to the central button is all made possible by reason of the stem 17 of the buttons extending from the periphery thereof. It will be understood, of course, that where a desired group for ornamental purpose is required, the button stems are arranged within the process of construction so that they may form a common stem for two buttons. Or, where stems of flexible material such as tape, ribbon or thread are employed, the desired group may be easily accomplished by stitching, tying or otherwise securing together the individual stems extending from the periphery of the buttons.

An ornamental device formed from buttons embodying this invention, such for example as shown in Fig. 3, may easily be secured as a whole to a lady's dress or like garment for decorating the same by stitching, pinning or otherwise securing the bottom faces of one or more buttons of the goods to the surface to be decorated.

It will thus be clear that I have provided a button which may be easily and inexpensively manufactured and which accomplishes in a practical manner the objects hereinbefore set forth.

Having thus described my invention, what I claim as new and desire to secure by Letters Patent is:

35 1. A button of the character described comprising two interlocking halves and a fixed stem extending from the periphery of the button and secured between said halves on the interlockment thereof.

40 2. A button of the character described, comprising a shaped upper half, a lower

half fitted thereto, and a fixed stem extending from the periphery of the button and held between two halves.

3. A button of the character described 45 comprising an upper half, a lower half fitted thereto, said upper half consisting of a suitably shaped shell and said lower half comprising a shell adapted to fit into said first mentioned shell, and a stem having a portion extending peripherally from the button, and a portion extending into said shells and held therebetween.

4. A button of the character described, 55 comprising an upper half, a lower half fitted thereto, said upper half consisting of a suitably shaped shell and a cover therefor and said lower half comprising a shell and a cover therefor, and a stem having a portion extending peripherally from the button 60 and a portion extending and held between said two halves.

5. As an article of manufacture, an ornamental unit for draping or decorating surfaces, comprising a plurality of buttons 65 having stems extending from the periphery thereof and connecting each pair of contiguous buttons, said buttons comprising each an upper and lower half fitted to each other, and said stems extending into said halves 70 and held therebetween.

6. As an article of manufacture, an ornamental unit for draping or decorating surfaces, comprising a plurality of buttons, each formed of two interlocking halves, and 75 stems extending from the periphery of the buttons for connecting each pair of contiguous buttons, the stems being secured between said halves on the interlockment thereof.

In testimony whereof I affix my signature.

HYMAN ROSEN.
